UNITED STATES PATENT OFFICE.

LESLIE A. HOLMAN, OF WALTHAM, MASSACHUSETTS.

NAILING MACHINE.

Application filed December 6, 1919. Serial No. 343,018.

To all whom it may concern:

Be it known that I, LESLIE A. HOLMAN, a citizen of the United States, and resident of the city of Waltham, in the State of Massachusetts and United States of America, have invented certain new and useful Improvements in Nailing Machines, of which the following is a full, clear, and exact description.

This invention relates to improvements in nailing machines and the primary objects of the invention are to secure great accuracy of nail feed and adequate support of the nail during driving, thereby avoiding bent or improperly driven nails.

Various other objects and advantages will be readily ascertained from the following description.

The device consists briefly of a frame carrying a reciprocating nailer head and a nail feeding device. The nailer head has resiliently connected thereto a nail holder to which nails are automatically supplied by the feeding device. A clutch is provided between the nailer head and the source of power and is adapted to be operated automatically or manually.

In the drawings which illustrate the invention;

Fig. 1 is a front elevation of the machine.

Fig. 2 is a side elevation of the machine viewed from the right.

Fig. 3 is a fragmentary side elevation viewed from the left.

Fig. 4 is a front elevation of the nail holder with the cover plate removed.

Fig. 5 is a vertical section of the complete nail holder on the line 5—5, Figure 4.

Fig. 6 is a longitudinal section of the nail feeding device.

Referring more particularly to the drawings, 11 designates the frame of the machine having at the top a bearing 12 in which the driving shaft 13 is journaled and at the front guiding fingers 14 and 15 which embrace the nailer head 16 and nail holder 17 respectively. The front end of the shaft 13 is rigidly connected to a disc 18, which reciprocates the nailer head 16 by means of a connecting rod 19. The disc 18 is provided with a rearwardly projecting flange 20, on which is mounted a brake band 21 retained in place by a ring 22 connected to the flange and held against rotating with the disc by

means of a tail 23, which is caught between the frame 11 and a bracket 24 secured thereto. The brake band is provided with any suitable grip adjusting means 25. A fly wheel 26 which also serves as a driving pulley is revolvably mounted on the shaft in rear of the bearing 13.

This fly wheel has fixed thereto a ring 27 provided with end facing teeth 28, adapted to mesh with the similar teeth 29 of a sleeve 30 slidably but irrevolvably mounted on the shaft in rear of the fly wheel. This sleeve is held against rotation on the shaft by a pin 31 projecting radially from the shaft through a slot 32 in the sleeve. The sleeve 30 is reduced in diameter in its rearward portion 33 and carries a relatively revolvble sleeve 34. As will be noted in Figure 3, the pin 31 is split horizontally so as to leave a flat surface 35 projecting radially from the shaft. The depth of this split need not be greater than the depth of the shoulder between the toothed and reduced parts of the sleeve 30. The sleeve 34 is provided on its forward end with a cam or ratchet tooth 36 adapted to co-operate with the pin 31. This sleeve 34 is provided with an operating lever 37 to which any suitable operating member 38 may be connected. The sleeve 34 is held against sliding rearwardly off the sleeve 30 by an adjusting nut 39, having a rearwardly extending threaded portion carrying a cap 39 which covers the extremity of the shaft 13. In rear of the sleeve 30 a collar 40 is adjustably mounted on the shaft 13, and a spring 41 is provided in compression between the collar and the rear end of the sleeve and operates to urge the sleeve forwardly and into engagement with the ring 27.

The nailer head 16 is merely a bar of metal sliding between the guides 14 and maintained by a cap plate 42. This head is provided with a longitudinal bore 43 to receive the nail driver 44, which is adjustably mounted therein by means of a set screw 44a.

The nail holder 17, which is located below the nailer head, is resiliently connected to the nailer head by means of a yoke 45 and springs 46 mounted on guides 47, rigidly connected to the yoke 45 and slidably in a yoke 48 secured to the bottom of the nailer head. Adjusting nuts 49 on the guide rods 47 regulate the distance between the nail holder and nailer head. The springs 46 are in compression between the yokes and serve

as a driving connection between the nailer head and nail holder, so that the nail holder is raised and lowered by the nailer head.

The nail holder, which is retained in the guides 15 by cap plates 50, comprises a body or back 51 and a cover or front plate 52. The yoke 45 is connected to the body 51 by means of a screw 53 and carries a dowel pin 54 to hold the lower end of the cover 52, which is attached at its upper end to the back by screws 55. The upper part of the body 51 projects farther forward than the remainder thereof and is provided with a groove 56 for the nail driver 44. Below the grooved upper portion of the body are a pair of nail holding fingers 57 pivotally mounted at their upper ends to the front surface of the body. The upper portions of these fingers are spaced apart sufficiently to give clear passage for the nail driver, but the lower parts are normally in contact and are provided on their contacting surfaces with grooves 58, which unite to form a nail passage. The lower end of this passage is so reduced in size that when the fingers are together the united groove ends form merely a pin-hole, so that the point of a nail in the grooves will come just to the ends of the fingers but will not pass through. The head 30 of the nail will lie above the upper ends of the grooves in the space between the fingers. The front surface of the body 51 is cut away, as at 59, and the lower ends of the fingers thickened so as to project into the cut-away portion, the upper limit of which is slightly above the upper ends of the nail grooves 58. A nail passage 60 is provided in the body leading from the rear surface thereof at the top through to the front surface at a point 40 slightly above the cut-away portion 59, and preferably inclined so that its axis approximately strikes the upper end of the nail grooves 58. The lower ends of the fingers are thickened on their front surfaces from their tips upwardly to a point above the upper ends of the grooves 58, and this thickened portion serves to provide guard plates 61, which meet to close the space between the fingers for a short distance above the grooves 58, so that a nail coming down the passage 60 and overshooting the grooves 58 will strike the plates 61 and be deflected into proper position. The cutting away of the lower portion of the body 51 and the rearward extension of the fingers thereinto effectually closes the crack between the fingers and body 51, so that it will be impossible for a nail to become accidentally caught between the fingers and body. Each finger 50 is provided with a spring 62 arranged in any suitable manner to urge the fingers toward one another. A stop pin 63 is provided for each finger and is positioned to prevent the finger swinging past the axis of the nail driver. The front plate 52 is pro-

vided with an opening 64 through which the feed of nails and the operation of the fingers and driver may be observed. In order that a shorter or longer nail driver may be substituted without the delay of removing the cap plates 50 and 52, the plate 52 is provided with a removable portion 65 located in front of the driver slot 56.

The nail feeding device comprises an oscillating magazine 66 discharging to a chute 67, which leads to the front of the machine and which preferably comprises a pair of bars 68, between which the nails hang by their heads. These bars are connected by bridges 69 and are supported on the frame by an adjustable bracket 70. The magazine may be arranged to serve one or more chutes, for the reason hereafter explained. The nail feeding device, to which the chutes deliver, comprises essentially a screw or worm 71 and a plate 72, against or adjacent to which the worm operates. The screw is preferably provided with a square thread equal to or slightly shallower than the diameter of the nail to be fed. In order to permit changes in the size of nails used, the screw is provided with a tapered shank 73, which enters a hollow driving shaft 74 and is secured by a pin or the like 75. The shaft 74 is journalled in a bracket bearing 76 secured to the frame 11, and carries revolvably mounted thereon a pinion 77 and rigidly mounted thereon a hand wheel 78. The hand wheel carries a pin 79 adapted to enter the pinion 77 and lock the two together. This pin is normally held in engagement with the pinion by means of a spring 80, which may, however, be swung to one side to permit removal of the pin and access to the bore of the shaft 74 for the purpose of driving out the screw 71. The counterplate 72, in conjunction with which the feed screw operates, curves gradually at its lower edge into an inclined trough 81 extending between the inner end of the screw and the upper end of the nail passage 60. The feed screw is driven by a chain 82 from a shaft 83. This shaft also operates as the timing shaft and controls the operation of the nail driver when the machine is operating automatically. If the machine is operated at irregular intervals, suitable connection must be established between this shaft or the feed screw and the shaft 13, in order to ensure the operation of the feeding device after each nailing operation. For the purpose of automatic operation, a cam 84 may be provided on the shaft 83 and arranged to operate the connecting link 38 once per revolution.

When the work to be nailed is of a nature which can be brought to the nailing machine at exactly regular intervals by means of a conveyor 85, the operation will be entirely automatic and the timing shaft 83 will be

set in proper speed relation with the conveyor to produce an operation of the nailing machine at stated intervals during the movement of the conveyor. When a conveyor is used, it is preferable to provide the same with apertures 86, through which the anvil 87 of the nailing machine may project, these apertures being slightly longer than the anvil. An adjustable stop 88 may be provided in the path of the yoke 45.

The operation of the device is extremely simple. Assuming the machine to be in proper working adjustment, the parts will be all in the positions shown, except that the cam 36 will be in engagement with the pin 31 holding the sleeve teeth 29 out of mesh with the ring teeth 28. The work to be nailed is placed on the anvil and the lever 37 depressed to revolve the sleeve 34 and move its cam tooth 36 past the pin 31. Owing to the splitting or flattening of the pin, this disengagement will be abrupt, as will be readily seen in Figure 3 and when effected will release the sleeve 30, so that the spring 41 will throw it against the ring 27 carried by the revolving fly wheel 26, so that the teeth mesh and the shaft 13 is revolved with the fly wheel. The sleeve 34 is, however, held against revolution by the operating link 38 or other suitable means. The connecting rod drives the nailing head 16 downwardly and this movement is communicated through the springs 46 to the yoke 45 and nail holder, so that the nail holder is moved downwardly into contact with the work on the anvil, whereupon its downward movement is stopped by the work. It will be seen that the lower extremities of the nail holding fingers are at the work engaging level and it will be remembered that the point of the nail is located at the very extremities of the fingers, in other words, the point of the nail is brought right to the surface of the work. When the downward movement of the nail holder is stopped by engagement with the work, the nailing head continues its downward movement compressing the springs 46 and thus putting considerable pressure on the work to hold it securely in place on the anvil or if it is of a soft nature to compact it suitably for nailing. The continued downward movement of the nailing head forces the nail driver 44 down between the fingers 57 and into contact with the nail head, which is forced between and separates the fingers and is finally driven down fully into the work. It will be seen that the nail point is in contact with the work before the driver touches the nail and also that if a proper length of nail is used the point of the nail will be set in the work, while it is still held by the fingers, and before the fingers have been forced apart to release the nail. Obviously under these conditions the nail point

cannot slip and the nail be driven on a slant or bent in the driving. This completes the first half revolution of the shaft. During the second half revolution, the nailing head rises to its proper distance above the nail holder, due to the compression of the springs 46, before the work is released. The nail holder is raised during the final part of the upward movement and as it is coming to rest in its uppermost position a nail is dropped by the feed screw 71 into the trough 81 and is thereby conducted into the passage 60 through which it falls into the grooves 58 of the closed fingers. During the final part of the upward movement, the cam 36 is engaged by the pin 31 and the sleeve 34 is thus forced rearwardly and carries with it the sleeve 30, so that on the completion of the revolution the teeth 28 and 29 draw out of mesh and revolution of the shaft stops. Immediately the driving force is taken off, the drag of the brake 21 stops revolution of the shaft. Owing to the fact that the fly wheel is the driving element, it will be understood that there is very little momentum in the shaft which must be absorbed before stoppage can be effected. Such momentum as there is is offset by the fact that all the moving parts of the machine are coming up to the dead centre. The nail magazine 66 may be connected with any suitable part of the machine to oscillate or jog the same, for the purpose of keeping the nails in motion, so that they work into the outlet slots of the magazine and into the chutes 67 down which they slide, hanging vertically from their heads. The feed chute and magazine perform a certain amount of selection, so that very badly deformed nails never reach the screw. Properly speaking, the chute should be full of nails between the feed screw and the magazine. As the screw is revolved in the direction of the arrow, Figure 1, that is upwardly on the side adjacent the plate 72, a turn in the groove thereof comes opposite the end of the chute and a nail slips into the screw groove filling this portion of the groove. If the nails are bent, finned, flattened or over-size, they will be a tight fit between the screw and plate 72, so that the movement of the screw will gradually raise them until they fall out over the top of the screw. If the nails are under-size or headless, they will fall through the screw. As the screw continues to revolve, the nails are carried laterally toward the centre line of the machine. The purpose of providing two or more chutes leading from the magazine is to ensure the placing of a nail in each turn of the screw groove, since if one turn was empty there would be no nail to feed after one of the operations. If, for any reason, the screw should fail to receive a nail from the first chute or to receive an imperfect nail and reject same, the

empty space in the screw will be filled when it passes the second or any subsequent chute. The presence of nails in the screw groove fills the groove opposite the chute end and prevents the entrance of further nails. These nails in the screw in combination with the thread of the screw serve as a closure or gate at the bottom of the second chute and operate to hold nails in the chute until a vacant turn of the groove comes opposite the chute. In a great many instances, it will be sufficient to have a single chute leading from the magazine and a second chute not connected with the magazine which may be filled by hand with perfect nails. The revolution of the screw carries the nails laterally until the end of the screw is reached and there is no further transporting means, so that the nails are released and slide point first down the trough 81. This enables the adjustment between the screw and counter plate 72 to be quite fine, so that a very accurate selection of nails will result. Obviously, the proper speed relation between the shaft 13 and feed screw is 1:1, but this relation may be obtained satisfactorily with a screw revolving continuously, for example, at ten revolutions per minute and a shaft operating intermittently at any greater number of revolutions per minute.

When the work to be nailed is brought to the machine on a conveyor 85, the downward movement of the yoke 45 presses the work down to the anvil, forcing the chain to sag down in so doing. If the openings 86 of the chain are of sufficient size, the chain will continue to move but the work will be held fast to the anvil during the nailing operation. This arrangement further ensures 40 against crookedly driven nails.

The machine has a number of advantages which will be readily appreciated by those skilled in the use of nailing machines. The device adapts itself automatically to work of varying thickness and holds the work securely on the anvil during the nailing operation. If any considerable or permanent change in the thickness of the work is encountered, the only adjustment required is to raise or 50 lower the nail holder by means of the nuts 49 and to adjust the driver 44. When a change is made in the length of the nail used, the only adjustments required are possibly a change of holding fingers and the 55 adjustment of the driver 44. While it is preferable to have substantially the whole length of the nail held by the fingers so as to absolutely centre the nail under the driver, it is obvious that as much as 25% of the 60 length of the nail may be above the ends of the grooves 58 without danger of crooked driving. Owing to the fact that the point of the nail is brought right to the work before nailing commences, the machine will 65 drive the shortest nails as accurately as the

longest within its capacity. Sinking nail heads into the work and clinching the nails is merely a question of selecting the proper length of nail and adjusting the driver 44. The provision of a limit stop 88 for the downward movement of the holder serves to check its movement if no work should happen to be placed under it and cause the driver to advance far enough to separate the fingers and allow the nail to drop, thus 70 emptying the holder ready for the reception of a fresh nail and so preventing clogging. The descending nail holder, which clamps the work to the anvil, eliminates movement of the work if fed by a conveyor during the 80 nailing operation and so avoids improperly driven nails. The nail feed is of the simplest possible character and will feed nails with absolute regularity, so that there will never be an empty holder when the nailer 85 descends. The releasable connection between the drive sprocket and feed screw enables accurate adjustment of the nail feed and also permits the operator to run the machine for examination without feeding nails, and also 90 to feed nails without running the machine when setting the machine up. The easily removable feed screw enables the machine to be readily changed to accommodate a different gauge of nail without the necessity 95 of making adjustments, as these are permanently made in the feed screws. The machine operates equally well whether actuated automatically or at irregular intervals by hand. 100

While the part 44 has been referred to as the nail driver and the part 16 as the nailer head, the term "nail driver" may be held to include both the parts 44 and 16.

Having thus described my invention, what I claim is:—

1. In a nailing machine, a nail driver, a nail holder positioned below the driver, a yoke on the nail holder, guide rods rigidly connected to the ends of said yoke having 110 slidable engagement with the nail driver, springs in compression between the yoke and driver, and adjustable stops on the guide rods limiting the separation of the driver and holder. 115

2. In a nailing machine, a nail driver, a nail holder, a nail feed screw, a timing shaft, driving connection between said timing shaft and the screw, a driving shaft for the nail driver, a continuously revolving pulley, a clutch adapted to connect and disconnect the pulley and driver shaft, and operative connection between said clutch and the timing shaft. 120

3. A device according to claim 2, in which the clutch is arranged to automatically disconnect the pulley and driver shaft on the completion of one revolution of the shaft, and in which the operative connection includes a cam on the timing shaft and a 130

link connecting said cam and clutch, the cam being arranged to operate the clutch once for each revolution of the feed screw.

4. The combination with a work conveyor of a nailing machine including nail holding and driving means on one side of the conveyor and an anvil on the opposite side of the conveyor, said nail holder being arranged to hold the work on the anvil during nailing independently of the movement of the conveyor.

5. A device according to claim 4, in which the conveyor is apertured at each work supporting point for the passage of the anvil and normally supports the work above the plane of the anvil and is adapted to be depressed by the nail holder to bring work into contact with the anvil through the conveyor apertures.

In witness whereof, I have hereunto set my hand.

LESLIE A. HOLMAN.
